DESIGN FOR A CRUCIBLE OR SIMILAR ARTICLE

John J. Ripich, Cleveland, Ohio

Application May 28, 1945, Serial No. 119,779

Term of patent 14 years

(Cl. D54—1)

To all whom it may concern:

Be it known that I, John J. Ripich, a citizen of the United States, residing in Cleveland, in the county of Cuyahoga and State of Ohio, have invented a new, original, and ornamental Design for Crucibles or Similar Articles, of which the following is a specification, reference being had to the accompanying drawing, forming part thereof.

Fig. 1 is a front elevation of a crucible embodying my new design.

Fig. 2 is a right side elevation thereof.

Fig. 3 is a plan view thereof.

Fig. 4 is a vertical axial section thru the crucible showing the conformation of the walls thereof in the plane indicated by lines 4—4 in Figures 1 and 3.

Fig. 5 is a horizontal section thru the crucible showing the conformation of the side wall thereof in the plane indicated by line 5—5 in Figure 2.

I claim:

The ornamental design for a crucible or similar article, as shown.

JOHN J. RIPICH.
